(57) **CLAIM**

The ornamental design for a display screen with animated graphical user interface for indicating buy/sell probability timeframes based on real time pricing, as shown and described.

DESCRIPTION

FIG. 1 is the first image in a sequence for a display screen with animated graphical user interface for indicating buy/sell probability timeframes based on real time pricing showing our new design; and,

FIG. 2 is a second image thereof.

The appearance of the animated user interface sequentially transitions between the images shown in FIGS. 1-2. The process or period in which one image transitions to another forms no part of the claimed design. The outer dotted line rounded rectangle shows the display screen and forms no part of the claimed design. All other broken lines show portions of the animated graphical user interface that form no part of the claimed design.
